POTATO PEELER OR THE LIKE

Noel James de Mille, Glasgow, Scotland

Application June 12, 1951, Serial No. 15,515
In Great Britain March 14, 1951

Term of patent 14 years

(Cl. D89—1)

To all whom it may concern:

Be it known that I, Noel James de Mille, subject of the King of Great Britain and Ireland, residing at 10, Sunnyside Avenue, Uddingston, Glasgow, Scotland, have invented a new, original, and ornamental Design for a Potato Peeler or the like, of which the following is a specification, reference being had to the accompanying drawing, forming part thereof.

Figure 1 is an elevational view of a potato peeler or the like, showing my new design.

Figure 2 is a plan view thereof.

Figure 3 is a left end view of Figure 1; and
Figure 4 is a right end view of Figure 1.

I claim:

The ornamental design for a potato peeler or the like, as shown.

NOEL JAMES DE MILLE.
